[57] CLAIM

The ornamental design for a barrette attachment, as shown and described.

DESCRIPTION

FIG. 1 is a front elevation of a barrette attachment in accordance with my new design;
 FIG. 2 is a top plan view thereof;
 FIG. 3 is a bottom plan view thereof;
 FIG. 4 is a left side view thereof;
 FIG. 5 is a rear elevation thereof, and;
 FIG. 6 is a right side elevation view thereof.
 The broken line showing of the barrette in FIGS. 2, 3, 5 and 6 is for illustrative purposes only and forms no part of the claimed design.
